UNITED STATES PATENT OFFICE.

CHARLES A. STOCKWELL AND WILLIAM D. ENSOR, OF BALTIMORE,
MARYLAND.

SAD-IRON.

SPECIFICATION forming part of Letters Patent No. 405,617, dated June 18, 1889.

Application filed September 12, 1888. Serial No. 285,178. (No model.)

To all whom it may concern:

Be it known that we, CHARLES A. STOCKWELL and WILLIAM D. ENSOR, citizens of the United States, residing at Baltimore, in the 5 State of Maryland, have invented certain new and useful Improvements in Sad-Irons, of which the following is a specification.

This invention relates to that class of smoothing or sad irons which are heated by 10 the internal application of a gas-flame. In this instance gas and compressed air are mixed and supplied to the heating-burner.

The invention is illustrated in the accompanying drawings, in which—

15 Figure 1 is a longitudinal vertical section of the improved iron. Fig. 2 is an end elevation of the iron. Fig. 3 is an end view of the top plug. Fig. 4 is a side elevation of the plug and burner. Fig. 5 shows two views of 20 the burner-disk. Fig. 6 shows two views of the burner-bushing which confines the burner-disk. Fig. 7 is a view of the iron with the 25 gas and air pipe connections. Fig. 8 is a vertical section of the iron, showing a modification.

25 The body A of the iron may have any desired shape, and has a cavity or chamber A', provided with a burner B, and at one end has a door or gate C, which opens and closes on 30 hinges a and affords access to the said chamber, and is opened when it is desired to light the burner.

35 The burner B may be attached to the top b of the chamber and open downward, as shown in Fig. 1, so as to direct the flame against the bottom, or it may be attached to the bottom d and open upward, as shown in Fig. 8. In either case the top b of the chamber has an opening c, which is closed by a screw-plug D. 40 By removing this plug access is afforded to the burner. The top plug D has some suitable provision—like a square head—to receive a wrench, whereby it may be readily turned. A duct e in the burner conveys the mixed gas 45 and air to the disk f of wire-gauze, or it may be a perforated plate. The disk is confined to its position by a ring or bushing g, which also serves as the opening or mouth of the burner. The burner-disk f is confined be- 50 tween a shoulder h and the said bushing g. In case the burner is attached to the bottom

d of the chamber, as in Fig. 8, the top opening c is necessary to enable the disk and bushing of the burner to be put in position and to be renewed or repaired, and, on the other hand, in case the burner disk and bushing are connected with the plug D, and thereby attached to the top of the chamber, the said top opening c is likewise necessary.

The body of the iron has a duct e', which 60 leads to the duct e of the burner. This duct e' is bored and its end closed by a plug i. The duct e' has at one end an opening, by which it may be connected with a gas-supply pipe or passage, by means of which gas may be 65 supplied in the interior of the sad-iron.

The burner shown in Figs. 1 and 4 has an exterior annular groove e² where the screw-thread e' of the top plug D is. The duct e in the burner has a right-angled bend, and the 70 upper part opens laterally at the annular groove e², which, when the plug D is in proper position, coincides with the duct e' in the body of the iron. This arrangement of annular groove e² to make connection with the 75 duct e' in the iron insures a full flow of gas and air to the burner, for it will not make any difference whether the screw-plug D is turned more or less.

A tube-nozzle F is attached to the iron and 80 makes connection with the duct e'. When the iron is in use, a hose or flexible supply-pipe G is attached to this nozzle.

A handle H, of wood or some poor conductor of heat, is attached by the end pieces j to the 85 iron. A flat shield-plate I is provided between the top of the iron and the handle, and is supported upon studs which form a space l, that separates the iron and shield-plate. The shield-plate I rests upon the studs l, which 90 are on the upper surface of the iron A, and screws m pass down through the handle end pieces j, shield-plate I, and into the studs l. Thus the studs l serve for attaching the handle to and also for supporting the shield-plate.

The gas and air pipes are shown in Fig. 7. The gas-pipe J has a cock n, and the air-pipe L has a cock o. The two pipes unite and form one supply-pipe G', to which the flexible pipe or hose G is attached.

Any suitable air-compressing apparatus

may be employed. The air-supply cock *o* may be used to control the supply of compressed air, so as to use more or less, and thereby regulate the character of the heating-flame within the chamber of the iron.

The modification shown in Fig. 8 locates the burner at the bottom. A deflector *P* is supported over the burner, and is attached to the screw-plug *D* by a screw *q*.

10 Irons of this kind may be used for a variety of purposes, one use being for pressing hat-bodies.

Having described our invention, we claim—

15 1. A sad-iron having a chamber *A'*, provided in the top with an opening *c*, and a screw-plug *D*, closing the opening, and a burner in the chamber having a perforated or wire-gauze disk *f*, confined by a mouth-ring *g*, as set forth.

20 2. A sad-iron having a chamber *A'*, provided in the top with an opening *c*, and a screw-plug *D* and a duct *e'* in the iron-body closed by a plug *i*, and a burner within the chamber

having a duct with a right-angled bend which connects with the said duct in the iron-body, 25 as described.

3. A sad-iron having a chamber *A'*, provided with a top opening *c*, and a duct *e'* in the iron-body closed by a plug *i*, and a screw-plug *D*, closing the top opening *c* and having attached 30 a burner whose supply-duct *e* is in communication with the said duct in the iron-body, substantially as described.

4. A sad-iron having a chamber *A'*, provided with a top opening *c* and a duct in the iron-body, and a screw supply-plug *D*, for closing said opening, and having an exterior annular groove *e²*, and a burner whose supply-duct *e* opens at said annular groove.

In testimony whereof we affix our signatures 40 in the presence of two witnesses.

CHARLES A. STOCKWELL.

WILLIAM D. ENSOR.
